United States Patent Office.

CHARLES T. FORD AND EDWARD TRASK, OF SALEM, MASSACHUSETTS.

Letters Patent No. 98,047, dated December 21, 1869; antedated December 7, 1869.

TOY-GUN.

The Schedule referred to in these Letters Patent and making part of the same.

To all whom it may concern:

Be it known that we, CHARLES T. FORD and EDWARD TRASK, of Salem, in the county of Essex, and State of Massachusetts, have invented a new and improved Toy-Gun; and we do hereby declare that the following is a full, clear, and exact description of the construction and operation of the same, reference being had to the accompanying drawings, making a part of this specification, in which—

Figure 1 is a top view of the gun.

Figure 2 is a longitudinal section, as indicated by line $x-x$ of fig. 1.

Like letters in both figures of the drawings indicate like parts.

Our invention has reference to a toy-gun for throwing torpedoes, peas, and other substances, and is intended as an improvement upon that patented by us, March 16, 1869, and consists in making a "kerf" in the head of the plunger, and also in the breech of the gun, and fastening the elastic in the same, thus dispensing with the nails or pins, which are liable to hurt or injure the children, and requiring less time and expense in applying the elastic.

A is the gun, having the "kerf" a cut in rounding or straight across the breech of the gun, and on a slant

from the surface thereof, to receive and hold the loop of the elastic B.

C is the plunger, having the "kerf" b cut in the head of it. Thus, by inserting the loop of the elastic in the "kerf" a , and the ends of the same in the "kerf" b , the elastic will be secured without pins or nails, and with less time and expense; and at any time, if the "spring" of the elastic or rubber should not be strong enough to impel the plunger with sufficient force to throw the torpedo or other substance, or if it should break, it can be easily tightened or replaced by another.

D is the hole for letting out the gravel or small stone after explosion of torpedo.

Having thus fully described our invention,

What we claim therein as new, and desire to secure by Letters Patent, is—

The "kerfs" a and b in the head of the plunger and in the breech of the gun, in combination with the elastic or rubber B, substantially as and for the purpose specified.

CHARLES T. FORD.
EDWARD TRASK.
